UNITED STATES PATENT OFFICE.

HOWARD S. KENNEDY, OF TROY, NEW YORK, ASSIGNOR, BY MESNE ASSIGNMENTS, TO
CLUETT, PEABODY & CO., INC., OF TROY, NEW YORK, A CORPORATION OF NEW
YORK.

COLLAR.

1,174,990.

Specification of Letters Patent.

Patented Mar. 14, 1916.

Application filed April 6, 1912. Serial No. 688,840.

To all whom it may concern:

Be it known that I, HOWARD S. KENNEDY, a citizen of the United States, residing at Troy, county of Rensselaer, and State of 5 New York, have invented certain new and useful Improvements in Collars, of which the following is a specification.

The invention relates to such improvements and consists of the novel construction 10 and combination of parts hereinafter described and subsequently claimed.

Reference may be had to the accompanying drawings, and the reference characters marked thereon, which form a part of this 15 specification. Similar characters refer to similar parts in the several figures therein.

Figure 1 of the drawings is a plan view of my improved collar laid out flat. Fig. 2 is a cross-section of the same taken on the 20 broken line 2—2 in Fig. 1 with the plies of fabric greatly exaggerated.

In certain forms of standing collars having end-wings and buttonholed end-tabs, it is found impossible to make the collar as an 25 integral construction where the bottom edge of the wing and the top edge of the button-hole-tab form a very acute reentrant angle. It has therefore been customary in making such wing-collars to form the body of the 30 collar with integral buttonhole-tabs and with separate inserted wings. The joining of the inserted wing to the body of the collar necessarily forms a ridge extending more or less obliquely across the body of the collar 35 to its top edge, the joint between the wing and the body of the collar being exposed to view on the top edge of the collar.

The object of the present invention is to make integral with the body of the collar, 40 end-wings forming a sharply acute reentrant angle with the respective buttonholed end-tabs.

In carrying out my invention, I cut away the body of the collar obliquely to its bottom edge along the lines of the bottom edges 45 of the respective wings and attach the end-tabs to the respective cut-away portions of the body of the collar.

Referring to the drawings wherein the in-

vention is shown in preferred form, 1, represents the body of the collar having the end-wings 2, 2 formed integral therewith. These end-wings are adapted to be folded over along the respective oblique lines, 3, along which lines would be formed the 55 ridges above referred to, if these wings were made separate and inserted in the usual manner. By making these wings integral with the body of the collar, the lines 3, 3 become more or less variable in their location, as the user can fold over more or less of the wing as he may desire, giving to the collar a degree of adaptability not found in the collar having inserted wings.

In carrying out my invention, I cut away 65 the ends of the collar at 6, obliquely to its bottom edge substantially along the lines of the bottom edges of the respective wings.

The end buttonholes, 4, are formed in end-tabs, 5, attached to the respective cut-away 70 portions, 6, of the body of the collar by inserting said tabs between the body plies and stitching said plies upon the inserted tab in the usual manner of inserting tabs.

I have shown the collar tab made of three 75 plies of fabric and the end-tab, 5, made of two plies of fabric, but either of said parts may be made of any desired number of plies.

By making the collar in the manner described, I am able to make the body of 80 blanks inturned on folding-machines and the end-tabs also of blanks inturned on folding-machines, the whole collar being thus made of machine-turned parts, which would be impossible in an integral construction of collar of the shape shown.

What I claim as new and desire to secure by Letters Patent is—

1. A standing-collar having a body-portion with obliquely truncated end-portions 90 adjacent to its lower edge and integral end-wings overhanging the respective truncated portions, and separate buttonholed end-tabs coinciding with, and secured to, the respective truncated end-portions of the body, 95 whereby said tabs form acute reentrant angles with the respective end-wings.

2. A standing-collar comprising a ma-

chine-turned body having integral end-wings, and separate attached inwardly flaring machine-turned buttonholed end-tabs forming acute reëntrant angles with said wings, the end of said body being cut away obliquely to its bottom edge along substantially the lines of the bottom edges of the respective wings, said end-tabs being attached to, and coincid-

ing with, the respective cut-away end portions of the body.

In testimony whereof, I have hereunto set my hand this 1st day of April, 1912.

HOWARD S. KENNEDY.
